UNITED STATES PATENT OFFICE.

JOSEPH W. FARLEY, OF EAST PITTSBURG, PENNSYLVANIA, ASSIGNOR TO WESTINGHOUSE ELECTRIC & MANUFACTURING COMPANY, A CORPORATION OF PENNSYLVANIA.

WINDING FOR ELECTRICAL APPARATUS.

SPECIFICATION forming part of Letters Patent No. 776,653, dated December 6, 1904.

Application filed March 16, 1904. Serial No. 198,506. (No model.)

To all whom it may concern:

Be it known that I, JOSEPH W. FARLEY, a citizen of the United States, and a resident of East Pittsburg, in the county of Allegheny and State of Pennsylvania, have invented a new and useful Improvement in Windings for Electrical Apparatus, of which the following is a specification.

My invention relates to windings for electrical apparatus, and particularly to the windings employed in transformers.

It has for its object to provide a coil of such construction that local and eddy currents may be reduced to a minimum and the resistances of parallel paths may be made approximately equal.

My invention is illustrated in the accompanying drawings, in which—

Figure 1 is a face view of a coil constructed in accordance therewith, a portion thereof being broken away to show the internal construction; and Fig. 2 is an end view of the coil shown in Fig. 1.

Transformers employed for transforming comparatively small currents at high voltages into very large currents at low voltages have but few turns in the secondary winding, and consequently the conductor must have a large cross-sectional area. If the conductor consists of only a single bar or strap wound edgewise, the electrical path at the outer edge thereof is of greater length than that at the inner edge, and local currents may therefore be produced in the conductor, the effect of which is to cause undue heating and possible injury to adjacent parts and also to absorb power, and thus reduce the efficiency of the transformer.

It is well known that excessive eddy-currents may be avoided by employing a plurality of relatively small insulated conductors wound in parallel instead of a single conductor having the same cross-sectional area, and it is by similar means that I am enabled to provide a conductor in which the production of local currents is reduced to a minimum.

In the construction of transformers of the "shell" type it is a customary practice to

employ flat coils placed side by side in parallel planes, so that if several conductors are wound in multiple it is desirable and generally necessary to wind them one outside of another. It follows from this method of construction that the outer strands have more resistance than the inner ones, because of their greater lengths, and hence local currents are likely to result. To avoid these difficulties, I have devised a coil of such construction that the parallel strands composing the conductor are approximately of the same length, and hence have substantially the same resistance.

Referring now to Fig. 1, in which a coil 1, composed of three turns or sections 2, 3, and 4, is represented, each turn of the coil is composed of four strands 5, 6, 7, and 8 of covered or insulated wire wound in multiple and one outside of another. It is to be understood, however, that the number of conductors and the number of turns shown are selected merely as examples and that any other numbers within practicable limits may be employed, if desired.

In order that the strands may all be of approximately the same length, the coil is constructed as follows: The four strands 5, 6, 7, and 8 are bent or wound in a clockwise direction in a single plane into substantially rectangular form beginning at the point 9 and ending at the corner 13. The strands are bent from that point laterally to the corner 10 and thence parallel to the corresponding side of the turn or section 2 to the corner 11. From the corner 11 the strands are bent at an angle somewhat more than ninety degrees, and each is given a return bend at such point 85 that all may cross each other and be reversed as regards their respective distances from the center of the coil—*i. e.*, the strand 5, which is on the outside between the point 9 and its return bend 14, becomes the inside strand, the strands 6 and 7 are changed at their return bends 15 and 16 from numbers two and three from the outside to numbers two and three from the inside of the coil, and strand 8 is changed at its return bend 17 from the inside 95 to the outside of the coil. From the corner

12 the strands are continued to the corner 13 and are then bent laterally to the point 10 and from that point are bent parallel to the section 2 to the point 9, where connection is 5 made with the external circuit.

It will be understood from the foregoing description and the accompanying illustration that all of the strands are of substantially the same length, since one and one-half turns of 10 each strand have a complementary relation to the other one and one-half turns as regards distance from the center of the coil. It is to be observed that the strands are not twisted, but are simply deflected to form the return 15 bends, and that the lateral space required by the crossovers is only twice the width of a single strand, because the crossovers are distributed. The turn or section in which the crossovers occur is generally interposed between other turns, and in order to avoid bulging the coil laterally and minimize the space occupied by the assembled coils in the same direction the portion of the turn 3 containing the crossovers is extended beyond the corresponding ends of the adjacent turns 2 and 4, so that the extra space occupied by the bulged or enlarged portions occurs at the end of the coil—a place where space is most available.

Although one set of crossovers per coil 30 will generally be found sufficient, the number is not limited to one, and if it is desired to only partially prevent the generation of local currents the crossovers may be located at some place other than the middle of the total 35 lengths of the strands. The strands of wire may be of different form in cross-section, and the coil may be of any other shape or dimensions within practicable limits, if desired.

It is to be understood that my invention is 40 not limited to coils for transformers of the shell type alone, but may be embodied in coils for other types of transformers, as well as in coils for other purposes. I do not wish my invention limited in other respects except as 45 restrictions may be imposed by the prior art.

I claim as my invention—

1. A coil for electrical apparatus comprising a plurality of suitably-insulated strands disposed one outside of another and in an unequal number of side-by-side sections or turns,

the strands of the middle turn or section being bent across each other so that substantially one half of each strand occupies a complementary relation to the other half as regards distance from the center of the coil. 55

2. A coil for electrical apparatus comprising a plurality of suitably-insulated strands disposed one outside of another and in a plurality of side-by-side sections or turns, the strands of one of the sections or turns being bent across each other so that approximately one half of each strand occupies a complementary relation to the other half as regards distance from the center of the coil. 60

3. A coil for electrical apparatus comprising 65 a plurality of suitably-insulated strands disposed one outside of another and transposed at a suitable point so that the active lengths thereof become approximately equal.

4. A coil for electrical apparatus comprising 70 a plurality of suitably-insulated strands which are transposed at one or more points so that the active lengths thereof become approximately equal.

5. A coil for electrical apparatus comprising 75 a plurality of strands in parallel and disposed in a plurality of turns or sections, the strands being crossed at one end of at least one of the turns or sections so that each strand occupies complementary relations at the sides of said 80 turn or section.

6. A coil for electrical apparatus comprising a plurality of turns of multiple strands disposed side by side in the planes of the turns, the several strands in the middle turn occupying 85 complementary relations at the sides of the coil as regards distance from its center.

7. A coil for electrical apparatus comprising three turns of multiple-wound strands disposed in the planes of the turns, the strands 90 at the sides of the middle turn occupying complementary relations as regards distance from the center of the coil.

In testimony whereof I have hereunto subscribed my name this 12th day of March, 1904. 95

JOSEPH W. FARLEY.
